UNITED STATES PATENT OFFICE

BENNETT F. CLARK, OF NEW BRUNSWICK, NEW JERSEY, ASSIGNOR TO JOHN WALDRON CORPORATION, OF NEW BRUNSWICK, NEW JERSEY, A CORPORATION OF NEW JERSEY

CONVEYER FOR SHEET DRIERS

Application filed October 21, 1930. Serial No. 490,255.

This invention relates to sheet driers, and more particularly to the construction of conveyers for sheet driers.

An important object of the invention is the provision of a conveyer structure for sheet driers of such character that neither the conveyer nor the supported trays interferes materially with the circulation of air through the drier.

10 A further object of the invention is to provide a novel and improved tray structure for use in sheet conveyers.

A still further object of the invention is the provision of a conveyer structure of this character wherein a selected tray or trays may be readily removed without interfering with the operation of the remainder thereof.

A still further object of the invention is the provision of a construction of this character wherein not only the tray but the tray support may be removed without interfering with the operation of the conveyer.

These and other objects I attain by the construction shown in the accompanying drawings wherein, for the purpose of illustration, I have shown a preferred embodiment of my invention and wherein:

Fig. 1 is a fragmentary side elevation of a conveyer for sheet driers constructed in accordance with my invention;

Fig. 2 is an enlarged transverse sectional view therethrough;

Fig. 3 is an enlarged fragmentary side elevation of a section of the conveyer;

Fig. 4 is a fragmentary enlargement of the structure illustrated in Fig. 2;

Fig. 5 is a section on line 5—5 of Fig. 4;

Fig. 6 is an enlarged fragmentary plan view of a section of the conveyer;

Fig. 7 is a fragmentary plan view of one of the trays;

Fig. 8 is a detail sectional view taken at a point indicated by line 8—8 of Fig. 7 through a pair of adjacent trays;

Fig. 9 is a detail sectional view through

the clamp employed for securing the trays to the conveyer flights;

Fig. 10 is a fragmentary sectional view similar to that of Fig. 6 showing a modified construction for providing a seat for the supported sheets;

Fig. 11 is a similar view of a further modification; and

Fig. 12 is a side elevation of the structure illustrated in Fig. 11.

Referring now more particularly to the drawings, the numeral 10 generally designates sprocket chains which, in the ordinary drier construction, operate over tracks 11 suitably supported within a housing 12. The working flight of the chain extends through the housing and the return flight may extend through the housing or not as desired, the articles to be dried being placed upon the trays of the working flight at one end of the housing and removed therefrom at the opposite end. The circulated heated air in the housing is generally admitted to the housing between the flights of the conveyer, as at points 16 distributed along the length of the housing, and passes upwardly between the trays to dry the surfaces of sheets supported

thereby leaving the housing through either an open top or, as disclosed in the present instance, through portals 17 formed in this top. The ordinary conveyer structure employed for this purpose is of such character that the trays or the tray supports tend to block the passage of air and interfere with its proper circulation. In accordance with my invention, the inner side plates 18 of the sprocket chain units 19 are each provided

at what are the outer edges thereof during useful travel of the conveyer with an inwardly-directed angular flange 20. The flanges of corresponding units are connected by metal cross bars 21 having their larger dimension vertically disposed as regards the central portion of the bar. At points immediately adjacent the ends of the bar a

sharp twist 22 is formed therein providing horizontally-disposed portions 23 which rest upon, and are secured to, the flanges 20 as at 24.

5 The tray 15 is preferably constructed as a skeletal frame embodying two or more feet 25 preferably forming end portions of the frame. This frame is likewise constructed of bar metal and the feet 25 thereof 10 are preferably presented to the supports formed by the cross bars 21 with their greatest cross sectional area in the direction of travel of the conveyer. As a means for attaching the trays to the cross bars, I provide 15 U-shaped clips 26, the arms 27 of which are perforated for the passage of feet as indicated at 28 and the cross bar 29 of which has a threaded aperture 30 for the passage of a set screw 31. The clips are placed against 20 the faces of the vertically-arranged portion of the cross bar and the feet 25 slipped through the openings 28 at the opposite side of the bar 21 from the cross bar 29 of the clip. The set screws 31 are then employed to draw 25 the feet against the cross bar and clamp the same thereto.

As a means for providing a seat for the lower edges of sheets supported by the tray, I secure to each of the outermost of the feet 30 25 a sheet support shown in Figs. 1 to 9 as an angle bar 32, these angle bars being of a length greater than the distance between adjacent bars 21 so that in the normal position of the trays and during flight travel 35 thereof the space between adjacent trays is bridged; alternate angle bar supports 32 at the same side of the conveyer are secured to opposite sides of their respective feet.

In Figs. 10 to 12, I have illustrated a modification of the method of providing the sheet supports 32. In these figures the sheets are illustrated as supported by means of the angular upper ends 35 of members 36 secured in assembled relation to the cross bar 40 21 and to the associated leg by clips 26—a similar to the clips 26 hereinbefore described. Each member 36 comprises an L-shaped piece of bar iron preferably of the same dimensions as that employed in the construction of 45 the tray. While independent clips might be employed for attaching one leg of each of these members 36 to the associated cross bar, I prefer that a single clip such as shown in Fig. 10 be employed, this clip having the 50 opening 28—a of sufficient width to accommodate passage both of the leg 25 and the attaching leg 37 of the member 36. The rear walls of these openings are angular as indicated at 38 so that when pressure is applied 55 through the adjusting screw 31—a the action of these walls upon the legs 25 and 37 tends to crowd the legs together so that they clamp not only against the bars 21 but against one another. The leg 35 of each member 36 is 60 preferably angularly deflected as more clear-

ly shown in Fig. 11, so that it will engage the opposite side of the leg of the following tray from that side at which it is disposed with respect to the tray leg against which it is clamped. If desired, however, the legs 70 35 may be made straight and the members 36 arranged upon opposite sides of the tray legs as suggested in Fig. 10.

In order that the upper ends of the trays 75 may be held in properly spaced relation, I provide each tray with a flat seat 33 arranged in the general plane of the tray and with a longitudinally-projecting tongue 34 which engages the seat 33 of the adjacent tray. It 80 will be noted from an inspection of Fig. 1 that sheets passing from the delivery conveyer DC onto the several trays will be deposited in these trays at a time when the trays incline downwardly from their inner or attached ends. The hooks formed by 85 tongues 34 serve to prevent the delivered sheet from sliding from the outer ends of the trays during the period when the tray is moving from its receiving position to a position where it inclines upwardly from the point of its attachment.

It will be obvious that a construction of this character provides an efficient conveying mechanism wherein a minimum resistance to the passage of drying air results.

It will also be obvious that this construction is capable of a certain range of change and modification without in any manner departing from the spirit of my invention, I 95 accordingly do not limit myself thereto except as hereinafter claimed.

I claim:

1. A conveyer for sheet driers comprising 105 endless side members, cross bars connecting said side members at spaced intervals, a tray associated with each cross bar and having feet to extend adjacent one face of the cross bar, U-shaped clips adapted to straddle the cross bar and having apertures for the passage of said feet and means for shifting the clips to force the feet into engagement with the cross bar.

2. A conveyer for sheet driers comprising 110 endless side members, cross bars connecting said side members, a tray embodying legs associated with each cross bar and having the legs thereof engaged against a longitudinal face of the associated cross bar, members associated with said legs and lying thereagainst and against the cross bar and a common means for forcing said members against the legs and against the cross bar and angular upper ends on said members projecting in the direction of travel of the conveyer.

3. In a sheet conveyer and in combination, 115 endless side members, cross members connecting the same, a tray associated with each cross member and having feet to extend adjacent one face thereof, U-shaped clips adapted to straddle the cross member and apertured 120

for the passage of said feet and L-shaped members adapted for passage through the apertures of the clips and means for shifting the clips to force the L-shaped members and
5 said feet into engagement with the cross bars, an end wall of each of the apertures having angularly related faces engaging the L-shaped members and the feet to cause them to move toward one another as the clips are
10 shifted.
